Fig. 3

Fig. 5

Fig. 4

Fig. 6

FIGURE 1 is a front view of the Space Condition Responsive Instrument embodying our new design as seen looking downward perpendicular to the dial face of the instrument;

FIGURE 2 is a true front view;

FIGURE 3 is a side view looking from the left of the instrument shown in FIGURE 2;

FIGURE 4 is a rear view;

FIGURE 5 is a cross sectional side view of the instrument shown in FIGURE 2; and

FIGURE 6 is a front cross sectional view of the instrument shown in FIGURE 3.

The undisclosed side of the space condition responsive instrument is substantially the same in appearance as the side shown in FIGURE 3.

The essential features of our disclosed design reside in the portions shown in full lines in the drawing.

We claim:

The ornamental design for a space condition responsive instrument, substantially shown and described.
